United States Patent Office

Des. 231,929
Patented June 25, 1974

231,929

NOZZLE FOR FAUCETS, CONDUITS, OR THE LIKE

Charles W. Ranson, 7906 Agnew Ave.,
Los Angeles, Calif. 90045

Filed Sept. 9, 1971, Ser. No. 179,252

Term of patent 14 years

Int. Cl. D23—01
U.S. Cl. D23—34

FIG. 2

FIG. 1

FIG. 3

FIG. 1 is a side elevational view of a nozzle for faucets, conduits, or the like showing my new design.

FIG. 2 is a top plan view.

FIG. 3 is a bottom plan view.

I claim:

The ornamental design for a nozzle for faucets, conduits, or the like, substantially as shown.
